UNITED STATES PATENT OFFICE

HORACE H. SEARS, OF NEW YORK, N. Y.

COLUMN

Application filed May 21, 1924. Serial No. 714,957.

The invention relates particularly to columns or shafts for use in place of wooden columns in mill and similar construction to improve the fire-proof quality of the building and incidentally to save the expense of wooden columns incident to the increasing cost of lumber. The scope of the invention is, of course, not limited to the field thus defined, the structure of the invention being obviously capable of a more general application.

The substitution of reinforced concrete columns for wooden columns is, of course, obvious in view of the present state of the building art. Such columns both molded in place and shipped whole have been used in numerous instances. The molding of columns in place has the disadvantage that the construction of the building must await the permanent setting of the concrete, as otherwise it cannot be depended upon to support the load and cannot be loaded without injury. Also the molds are an important expense item. The columns which are shipped whole are difficult and expensive to handle and to ship.

The present invention relates to a concrete column or shaft built up of separate concrete blocks which may be either hollow or solid, and reinforced vertically and transversely by means of suitable tension rods. Columns built in this way are much cheaper to ship and to handle and to construct, and will support the load immediately after they are set up. The rods also resist shearing.

In accordance with the preferred form of the invention the blocks are provided with aligned grooves to receive the vertical reinforcing rods, and they may be grooved transversely to receive the transverse rods, or these rods may be embedded in the individual blocks as hereinafter described.

In the use of the column the blocks are shipped separately and the columns are formed in the construction of the building by placing the blocks one on top of the other on suitable foundations, base blocks or standards. In placing the blocks it is necessary that the vertical grooves be placed in alignment to receive the vertical reinforce. The transverse reinforce may, as stated, be placed

in transverse grooves or embedded in the blocks as formed. In any event the vertical and transverse reinforcing rods are connected at the intersections, and the grooves are filled with a mixture of cement and sand or other suitable material which serves to cover and protect the reinforce and give the column the desired finished appearance. While I have referred to concrete as the commonest and most easily available material for the construction of the blocks, they may be formed of any mineral plastic which takes a rigid non-fluid set, as clay, lime, Portland or natural cement with any suitable fillers.

The blocks may be hollow, i. e., may be formed in vertically extending tubular sections or solid, or the hollow sections may be filled with concrete and tamped as they are set up and permitted to harden in place, saving the cost of the mold, as the finished column may be hollow.

In the accompanying drawing I have illustrated a sectional column built up of concrete or shaft blocks in accordance with my invention. I have also illustrated these blocks in detail in two forms.

In the drawings—

Figure 1 is an elevation of a column or shaft in accordance with my invention, the same being shown in the course of construction for convenience in illustrating the arrangement of the reinforce.

Figure 2 is a section on the line 2, 2 of Figure 1.

Figure 3 is a perspective view of the block used in said column.

Figure 4 is a perspective view of a shaft block of somewhat different construction; and

Figure 5 illustrates a section of column or shaft made from a block of the type illustrated in Figure 4.

Referring to the drawings by numerals, each of which is used to indicate the same or similar parts in the different figures of the drawings, the column 1, shown particularly in Figures 1 and 2, is formed of a series of concrete blocks 2. These blocks as shown are elongated in the direction of their height. They are preferably of rectangular cross-

section and are grooved at 3 in a vertical direction, the vertical grooves being shown in the centre of each lateral face and the horizontal grooves in the preferred form shown in Figures 1, 2 and 3 being one at each end of the column and one at the middle extending around the periphery, the middle groove 4 being preferably of twice the width of the end grooves 5 and 6, so that when the blocks are assembled to form the finished column, as shown, particularly in Figure 1, the vertical grooves 3 being placed in alignment to form the continuous vertical groove 7, the end grooves of the adjacent blocks are combined to form a single groove. The blocks 2, as shown in Figure 3, may be hollow or tubular, the hollow being indicated by reference character 8, and the hollow may, if desired, be filled with concrete after assembling, or more properly during the process of assembling, the concrete being tamped as the assembling operation proceeds. As soon as the blocks are set up, vertical reinforcing rods 9 of a section to suit the load and unsupported length, are placed in the vertical grooves 7 formed by placing the grooves 3 in alignment and are suitably connected to the transverse reinforce 10 which may be placed in the transverse grooves 4 at this time, or may be placed in the blocks as formed and in a manner hereinafter described. The connection may be formed by wrapping wire about the intersecting rods or otherwise. When the reinforce is suitably placed, the grooves are then filled with cement or cement putty 11, as indicated, particularly in Figure 2, and when this material has hardened, the assembled column has all the desirable properties of a reinforced concrete column molded in a single piece, it being understood that the blocks thus placed will resist the stresses of compression as efficiently as will a continuous column of similar section, and as the concrete is not relied upon to resist tension stresses, the reinforce being provided for this purpose, the column is practically as efficient as a column of similar section and length cast in a single piece, and similarly reinforced.

In Figures 4 and 5 I have illustrated a shaft block and a section of column made of a shaft block having the transverse reinforce 14 embedded therein. These shaft blocks 15 are of semi-circular cross-section, and of suitable length, and have each one or more reinforcing members 14 embedded in the material of which the block is formed, and extending around the block in the direction of the circular periphery, the ends 16 of the reinforce protruding from the edges of the block, which is shown as hollow, though this is not essential. The reinforce is formed with eyes 17 one at each end. In assembling the column the blocks are placed one on top of the other, the completed column being formed by plac-

ing the blocks in pairs of blocks 18, 19, comprising a complete section, see Figure 5, with the corresponding eyes 17 of the transverse reinforce in each block in registration. The straight edges 20 are preferably shouldered or rabbeted at 22 to provide room for the vertical reinforcing members 21 which are placed in the groove 23 thus formed between the edges of the blocks and passed through the eyes. When the reinforce has been placed, the groove 23 is filled with cement or cement putty or the like covering the previously exposed portions of the reinforce. It is apparent that the sections 18, 19, Figure 5, may be built up of any desired number of pieces depending upon the number of spaces for vertical reinforce desired, and also that the two methods of placing the reinforce illustrated, particularly in Figures 1 and 5 may be combined.

Having thus described specifically and in detail a preferred and secondary form of shaft block and assembled shaft or column embodying the features of my invention in the preferred and in a secondary form, I would have it understood that the specific terms herein are used descriptively rather than in a limiting sense, the scope of the invention being defined in the claims.

What I claim and desire to secure by Letters Patent is:

1. A reinforced column composed of separate blocks of molded mineral plastic having aligned grooves in the direction of the length of the column, vertical reinforcing members therein, and transverse reinforcing members secured to said vertical reinforcing members.

2. A reinforced column consisting of a series of grooved blocks of mineral plastic, one on top of the other, the grooves being placed in alignment providing a vertically extending channel, a vertical reinforce extending substantially the length of said column in said space, and transverse reinforcing members at intervals extending around the column intersecting the vertical reinforce and secured to said vertical reinforce at the intersections.

3. A column composed of a series of separate concrete blocks placed one on the other, the blocks having vertical and transverse grooves, the vertical grooves being placed in alignment, vertical reinforcing members in the vertical grooves, and transverse reinforcing members in the transverse grooves.

4. A reinforced column composed of separate blocks of molded mineral plastic having grooves aligned in the direction of the length of the column and vertical reinforcing members therein, the blocks also having transverse grooves and transverse reinforcing members therein and plastic material covering the reinforce in the grooves.

5. A reinforced concrete column consisting of separate blocks of molded mineral plastic,

each of said blocks having a horizontal cross section comprising substantially the entire horizontal cross section of the column and the respective blocks having aligned grooves in their outer surfaces, extending in the direction of the length of the column, reinforcing members therein extending substantially the entire length of the column and plastic material covering the reinforcing members in the grooves.

5 Signed by me at New York, New York, this
10 16th day of May, 1924.
